UNITED STATES PATENT OFFICE.

EDWARD M. BARNES, OF HASTINGS, MICHIGAN, ASSIGNOR TO ADVANCE MANUFACTURING COMPANY, OF HASTINGS, MICHIGAN.

DESIGN FOR A VACUUM-CLEANER CASING.

44,511.

Specification for Design.

Patented Aug. 19, 1913.

Application filed May 7, 1913. Serial No. 766,194. Term of patent 14 years.

To all whom it may concern:

Be it known that I, EDWARD M. BARNES, a citizen of the United States, residing at Hastings, in the county of Barry, State of Michigan, have invented a new, original, and ornamental Design for a Vacuum-Cleaner Casing, of which the following is a specification.

My new, original and ornamental design for vacuum cleaner casing is clearly illus-

trated in the accompanying drawing which is a perspective view thereof.

I claim:

The ornamental design for vacuum cleaner casing as shown.

EDWARD M. BARNES.
